WELL PACKER

Jesse Gannon, Culver City, Calif., assignor to
Ben Weingart, Los Angeles, Calif.

Application August 11, 1951, Serial No. 241,409

17 Claims. (Cl. 166—12)

1

This invention has to do with well packers, it being a general object of the invention to provide a packer construction operable in a well to pack between parts located in the well and which is such that it can, when it is desired or necessary, be easily and quickly removed or freed allowing relative movement between the parts packed.

There are many situations in wells where it is desired to seal or pack between parts or elements and it is common practice in such situations to employ soft packers, that is, packers made up of materials subject to expansion or deformation. It is common to employ rubber or rubber-like materials in well packers and in many situations a series of packers is required, and in such cases several rings of packing material are employed, and when set they are expanded to have tight sealing engagement with the parts between which they pack. It is generally practical to provide effective or efficient packing arrangements of the character mentioned. However, in practice the usual or conventional packers of the type referred to when set under pressure, and after having remained set for an appreciable length of time, become bonded to the parts between which they seal in such manner as to make their removal or release difficult, if not impossible.

It is a general object of this invention to provide a construction wherein a plurality of packers or sealing rings is provided to seal between well parts and in which packing releasing means serves to release the packers or rings even though they are tightly engaged with or bonded to the parts with which they engage.

It is another object of this invention to provide a well packer of the general character referred to wherein there are several packing rings and in which the structure is such that when it is operated to release the rings they are released successively, thus requiring only a maximum force necessary to release but a single ring.

It is another object of this invention to provide a well packer of the general character referred to which involves general construction similar to that commonly used in well packers and known to be effective and satisfactory, while at the same time incorporating features of construction which facilitate release and removal in the manner above set forth.

Another object of the invention is to provide a well packer of the general character referred to which involves few simple parts that are inex-

2

pensive of manufacture and which are effective and dependable in action.

It is a further object of the invention to provide a well packer of the general character referred to having the desired releasing action mentioned and which is such that it can be advantageously incorporated in a structure no more cumbersome or of no greater size than is ordinarily employed in a conventional packer.

The present invention can be incorporated to advantage in various well packers intended to be released and since such packers are employed under various conditions or in connection with various well parts, the present invention can be carried out under varying conditions or circumstances. In the following disclosure and in the drawings the invention is shown incorporated in what may be termed a simple and more or less conventional packing construction, serving to pack between a well tubing, or an extension thereof, and a well casing in which the tubing or extension is located. The construction illustrated is not of the simplest form, since it includes a casing gripping means and a control therefor, and it further involves a flow control or valve means around the packers and various advantageous features of construction of this kind. It is to be understood that the following description, which is of a single typical construction incorporating the invention, is not to be in any way construed as limiting the broader principles of the invention to this or any other specific application.

In the application of the invention here disclosed there is a body which is elongate and tubular in form and which includes a main or upper section and a lower or clamp section. A core is attached to or coupled with a well tubing, or the like, and depends therefrom through or into the body. The core is related to the body and limited relative movement is provided between the core and the body, the body being movable between a coupler that connects the core and the tubing and a shoulder on the core which faces upwardly and is engageable with the lower end of the main section of the body. The packers are preferably alike and may be simple rings of packing, separable from one another, and they are preferably in a series that extends longitudinally of the body so that they are one above the other. The packing rings are proportioned so that their inside diameters slidably accommodate the main section of the body and they are subject to being expanded or deformed so that their outer peripheries engage and seal with

the interior of the casing occurring in the well. In a typical arrangement the lowermost packing ring rests on the collar at the upper end of the lower body section and the upper ring bears against a collar on the main body section. Any intermediate packing rings are between those engaged with the collars. The lower body section is movable longitudinally of the main body section and as the collars of the body sections approach each other the packing rings between the collars are compressed so that the desired sealing engagement is established between the body and the casing.

Packer releasing means is provided and in the case illustrated involves pullers or lifters between the packing rings other than the one resting on the collar of the lower body section and links operatively connect the lifters and the main body section so that lifting of the main body section relative to the casing and relative to the packing rings set against the wall of the casing results in the lifters being actuated one after the other, with consequent lifting of the packing rings one after the other and not simultaneously.

A casing gripping means is provided, preferably on the lower section of the body, and is shown as involving a wedge depending from the body, and slips operated by the wedge to engage and grip the casing. A sleeve is shiftable on a depending extension of the wedge and links connect the sleeve and the slips. A control is provided for the gripping means and may include friction members carried by the sleeve and bearing outwardly against the casing, and a bayonet slot construction controls movement of the sleeve longitudinally of the depending extension on which the sleeve is carried. A flow control or valve means is provided so that the elements packed by the packing rings can be bypassed for flow through the structure in either direction, as circumstances may require.

The various objects and features of my invention will be fully understood from the following detailed description of a typical preferred form and application of the invention, throughout which description reference is made to the accompanying drawings, in which:

Fig. 1 is a view illustrating a packer embodying the present invention, showing it located in a well casing and related to a well tubing extending into the casing. Fig. 2 is an enlarged plan section taken as indicated by line 2-2 on Fig. 1. Fig. 3 is an enlarged plan section taken as indicated by line 3-3 on Fig. 1. Fig. 4 is an enlarged plan section taken as indicated by line 4-4 on Fig. 1. Fig. 5 is an enlarged longitudinal sectional view of a portion of the structure, being a view taken substantially as indicated by line 5-5 on Fig. 2. Fig. 6 is a view similar to Fig. 5, showing the structure operated to release one of the packing rings. Fig. 7 is a view similar to Fig. 6, showing the structure further operated so that an intermediate packing ring is released, and Fig. 8 is an enlarged plan section taken as indicated by line 8-8 on Fig. 6.

The structure illustrated in the drawings and in which the present invention is incorporated is shown acting in connection with a well casing A and a tubing B in the casing, the tubing being considerably smaller in diameter than the casing so that there is a flow passage between these elements. A tubular body C is provided and carries a plurality of packers D. A core E is carried by the tubing B and extends into the body C

and is cooperatively related thereto, these elements being related for limited movement relative to each other longitudinally of the structure. A packer releasing means F is provided whereby the structure can be operated so that the packers D are released separately, or individually one after the other. A casing gripping means G is provided and can be set or actuated to check downward movement of a section of the body. A control means H is provided for the gripping means G. A flow control or valve means J is provided controlling flow through the structure past or through the packers, and the structure includes various other details and features as will be hereinafter described.

The body C is an elongate tubular structure and in the case illustrated it is a sectional structure involving a main or upper section 10 and a clamp or lower section 11. The upper section 10 of the body is a tubular element of substantial length passing the core E so that there is an annular fluid passage 12 between these elements. The upper section 10 of the body is considerably smaller than the well casing so that there is an annular space 13 between the casing and body section 10, and it is this space that is sealed off or packed by means of the packers D, as will be hereinafter described.

In the particular construction illustrated the body section 10 is related to the core E so that limited movement can occur between these elements longitudinally of the structure. The body section 10 is shown as being shorter than the core E and it is confined between the coupler 15 by which the core is connected to the tubing B and an upwardly facing shoulder 16 that occurs on the core E well below the coupler 15, as clearly illustrated in Fig. 6 of the drawings.

When the core is in what may be considered a down position relative to the body section 10 the coupler 15 is, in effect, engaged with the upper end of body section 10, the engagement being through the flow control J, as hereinafter described. When the structure is operated to release the packers D the shoulder 16 of the core is engaged with the lower end of body section 10, as illustrated in Figs. 6 and 7 of the drawings.

The engagement between the body section 10 and the core obtained through the shoulder 16 of the core is preferably such as to provide for passage of fluid through the passageway 12, while the core is engaged with the body section 10, as shown in Figs. 6 and 7. In the case illustrated the shoulder 16 is an annular shoulder facing upwardly and occurs between the upper portion 20 of the core and the enlarged depending lower portion 21 of the core. A plurality of inwardly projecting lugs 22 occur at the lower end of body section 10 and it is these spaced lugs that engage the shoulder 16, providing the desired engagement between the core and the body section 10. The lower ends of the lugs 22 engage the shoulder 16 while the inner edges of the lugs engage the exterior of the portion 20 of the core and maintain the core centrally in the body section 10.

The clamp or lower section 11 of the body is a tubular element somewhat larger than the upper section 10 and its upper end portion is telescopically related to the lower portion of body section 10, as shown in the drawings. A collar 23 on the upper end of body section 11 slidably fits on or passes the body section 10 and presents a downwardly facing shoulder 24 that opposes and cooperates with an upwardly facing shoulder 25 on

an enlargement 26 at the lower end of body section 10.

The parts just described are related and cooperate so that after a limited upward movement of the body section 10 relative to the section 11 the shoulders 24 and 25 engage and further upward movement of body section 10 will cause the section 11 to be carried with it.

The packers D are carried by or on the body section 10 and in accordance with the present invention there are several packers D and they are such as to be, in effect, packers related to operate simultaneously and in like manner to seal between the body section 10 and the interior of casing A. In a typical situation each packer D may include one or more rings 38 of packing material and in the case illustrated each packer D includes two rings of packing material slidably engaging the exterior of the body section 10 and proportioned so that when in normal position or unactuated their outer peripheries 31 are spaced from the interior of casing A.

In accordance with the present invention the number of packers D incorporated in this structure may be varied widely. In the particular case illustrated there is what may be termed a lower packer D which engages and rests upon the upper end of the lower body section 11, there is an upper packer D which engages a collar 35 on the body section 10, and there is an intermediate packer located between the upper and lower packers. The lower packer D rests on the upper end of collar 23 that occurs at the upper end of body section 11. The collar 35 provided on the body section 10 is located on body section 10 well above the collar 23 and it faces downwardly so that the upper packer D engages it, as clearly illustrated in Figs. 5, 6 and 7 of the drawings. The intermediate packer D occurs on the body 10 between the upper and lower packers and is free of engagement with collars such as those above described.

The several packers D are preferably formed of one or more rings of conformable or expandible packing material such as rubber or rubber-like material, and the packers occur on or are related to the body so that when the body sections 10 and 11 are moved relative to each other to advance the collar 23 toward the collar 35, the several packers are compressed, with consequent expansion of the packer rings so that they seal tight on the exterior of the body section 10 and in or against the interior of the well casing A.

In accordance with the present invention the packer releasing means F is provided and is such that when the body is operated from a position such as I have just described, as by moving the body sections relative to each other so that the collars 23 and 35 move apart, the packers D are successively released or are released one after the other. In the form illustrated the means F includes ring pullers or lifters 40 in connection with the packers and links 41 relating the lifters 40 with the body C.

In the case illustrated a lifter 40 is provided in connection with each of the packers D, except the lower packer which is engaged with collar 23, and each lifter 40 is in the form of a simple annular element slidably engaged around body section 10 and located immediately below the lowermost ring of the packer with which it is related. As will be observed from the drawings, the upper packer D and the intermediate packer D each has a lifter 40 engaged under it, this relationship

of parts being best illustrated in Fig. 7 of the drawings.

The links 41 connect the lifters 40 with the body section 10 and in the case illustrated each lifter 40 is coupled with the collar 35 of body section 10 by a plurality of links 41. The several links are circumferentially spaced around the body and are preferably simple elongate bars or rods having their lower ends anchored to the lifter while their upper ends are slidably engaged in openings 43 extending through the collar 35 longitudinally of the structure. In the case of the links 41 related to the lifter for upper packer D, the links 41 extend upwardly through openings 44 in the ring of that packer. In the case of the links 41 related to the intermediate packer the links extend upwardly through the rings of that packer, through openings 45 in the lifter of the upper packer, through openings 44 in the rings of the upper packer and to the collar 35.

The links 41 related to the lifters 40 are of such length that when the several packers D are set, as shown in Fig. 5, the heads 46 on the links related to one packer, for instance the upper packer, are spaced a short distance above the collar 45, whereas the heads 46 on the links related to the intermediate packer are spaced a substantial distance above the collar 35. As a result of this relationship of parts when the structure is operated so that body section 10 moves up relative to section 11 to effect release of the packers D, collars 35 and 23 move apart, the heads 46 on the links related to the uppermost packer D are engaged by the collar 35 with consequent force being applied to the rings of the uppermost packer causing freeing of that packer from the wall of the well casing, so that it will slide therein. Continued upward movement of section 10 will result in collar 35 engaging the heads of the links related to the intermediate packer, with the result that the intermediate packer is freed so that it will slide in the casing.

In accordance with the present invention the parts are so related that following freeing of the intermediate packer through the action just described the shoulder 25 on the enlargement 26 at the lower end of the body section 10 engages the shoulder 24 of collar 23, causing collar 23 to be moved upwardly in casing A with consequent freeing of the lower packer from the casing so that it will slide therein.

In the particular structure illustrated there is a casing gripping means G and this is shown as involving a wedge member 50 carried by and depending from body section 10. Slips or casing grippers 51 are engaged with wedge faces 52 and are operated by means of a sleeve 53 through links 54. The sleeve 53 is slidable on the lower portion 60 of the core E.

The control means H for the gripping means G is shown as a conventional control involving a plurality of members 60 frictionally engaged with the casing A and related to the sleeve 53. The members 60 are shown as outwardly bowed leaf springs anchored to the lower end of sleeve 60 by fasteners 61. The upper ends of the springs are connected to a ring 64 that slides on the sleeve. A bayonet slot control involving a pin 65 operating in an L-shaped slot 66 in the sleeve 53 provides a releasable lock so that the means H can be set with the sleeve in a down position on the core to facilitate lowering of the structure into the casing. When it is desired to set the packer the pin 65 is operated in the slot to

enter the vertical part thereof whereupon lowering of the body causes the wedge 30 on the body to enter between the slips 51 so the slips are wedged into engagement with the casing. Through this operation the gripping means G forms a fixed abutment or stop in the casing. With the casing section 11 thus stopped collar 23 on section 11 will not move down and therefore further downward movement of the body section 10 will cause collar 35 thereon to compress the several packers, as hereinabove described.

The flow control means J incorporated in the particular construction illustrated involves a seat 70 on or at the upper end of body section 10 and a valve element 71 on the core or on the coupling 15 connecting the core with the tubing. In the particular case illustrated the seat 70 is an annular member threaded onto the upper end of body section 10 and the valve 71 is an annular valve element provided at the lower end of collar 15 and surrounding the core E where the core connects to the collar.

The parts just described are such that when the tubing B is moved downwardly after the means G has been engaged, the flow control J will operate to stop flow through the body due to the valve 71 engaging the seat 70. Further downward movement of the tubing B results in depression of the body section 10 relative to section 11 with consequent movement of collar 35 toward collar 23, which results in compression of the packers.

The mechanism is such that so long as the tubing B bears downwardly on the body section 10 the packers are maintained under compression and in consequent sealing engagement between the body section 10 and the casing A. When the structure is to be released initial upward movement of the tubing B opens the flow control J so that fluid is free to flow through the body 10 even though the packers D are still in sealing engagement between the body section 10 and the casing A. After a predetermined upward movement of the core E has occurred relative to body section 10 the shoulder 16 of the core engages the lower end of body section 10 so that further upward movement of the core due to lifting of the tube will result in the successive release of the packers, as hereinabove described.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A well packer including, a body having sections with spaced opposed parts, one section being an elongate tubular main section and the other section being an annular clamp section surrounding and shiftable longitudinally relative to the main section, a plurality of separable packers in a series extending lengthwise of the main section and between said parts and each slidably carried on the main section and adapted to be compressed between said parts upon the sections being moved in one direction relative to each other, and a member connected to each packer and slidably connected to the main section for limited movement relative thereto, the members being of different lengths and adapted to successively pick up the packers for movement

with the main section upon relative movement between the sections in the opposite direction.

2. A well packer including, a central tubular body having a main elongate tubular section and an annular clamp section surrounding and shiftable relative to the main section, the sections having spaced collar portions thereon, a plurality of separable packers slidably on the main section in a series lengthwise of the main section and between the collars, the packers being adapted to be compressed by and between the collars upon the sections being moved in one direction relative to each other, and a member connected to each packer and slidably connected to the main section for limited movement relative thereto, the members being of different lengths and adapted to successively pick up packers for movement with the main section upon relative movement between the sections in the opposite direction.

3. A well packer including, an elongate central body having a main tubular section and an annular clamp section slidable on the main section and adapted to shift relative to the main section lengthwise thereof, the sections having collar portions opposed to each other, a plurality of separable packers slidably carried by the main section between the collar portions and adapted to be compressed by and between the collar portions upon the sections being moved in one direction relative to each other, and members extending longitudinally of the body and each slackly linked to the collar of the main section and each engaged with a packer, the said members being of different lengths and adapted to successively pick up packers for movement with the main section upon relative movement between the sections in the opposite direction.

4. A well packer including, an elongate central body having a main tubular section and an annular clamp section slidable on the main section and adapted to shift relative to the main section having collar portions opposed to each other, a plurality of separable annular packers slidably carried on the main section between the collars and adapted to be compressed by and between the collars upon the sections being moved in one direction relative to each other, and members connected to the collar of the main section and each engaged with a packer, said members being adapted to successively pick up packers for movement with the main section upon relative movement between the sections in the opposite direction, each packer including a ring of packing around the main body section and each member including an annular part engaged around the main body section and engaging the ring of a packer and a part extending longitudinal of the body and engaged with the main section, the said parts of said members being of different lengths.

5. A well packer including, a body having an elongate central main section and an annular clamp section shiftable lengthwise relative to the main section, each section having a collar thereon, the collars being spaced apart and opposed, a plurality of separable packers slidably carried on the main section between the collars and adapted to be compressed by and between the collars upon the sections being moved in one direction relative to each other, and members of different lengths slackly linked to the main section and each engaged with a packer, said members being adapted to successively pick up packers for movement with the main section upon

relative movement between the sections in the opposite direction, there being one packer in addition to those engaged by said members and engaged by the collar of the clamp to be picked up thereby.

6. A well packer including, an elongate body having an elongate main section with an annular collar fixed thereon, a clamp section surrounding and shiftable longitudinally of the main section and having a collar thereon spaced from and opposing the collar of the main section, a plurality of separate annular packers slidable on the main section and arranged in a series between the collars, annular lifters on the main section and spaced apart longitudinally thereof, each lifter being engaged with a packer, and separate members extending longitudinal of the main section and connecting the lifters and the main section for different degrees of relative movement lengthwise of the main section whereby the packers engaged by the lifters are successively picked up to move with the main section when the sections are moved relative to each other so the collars move apart.

7. A well packer including, a body having an elongate main section with a collar thereon, an annular clamp section surrounding the main section below said collar and shiftable longitudinally of the main section, the clamp section having a collar thereon, means limiting relative movement between the body sections lengthwise of the main section, a plurality of separate annular packers slidable on the main section and located between the collars, annular lifters on the main section and each engaged with a packer, and members of different lengths extending longitudinal of the main section and connecting the lifters and the main section whereby the packers engaged by the lifters are successively picked up to move with the main section when the sections are moved relative to each other so the collars move apart, there being one packer in addition to those engaged by the lifters and being engaged by the collar of the clamp section.

8. A well packer including, a central body having a main elongate section with a collar fixed thereon, an annular clamp section shiftable longitudinally on the main section below the collar of the main section and having a collar thereon, a plurality of separate annular packers slidable on the main section and located between the collars, annular lifters on the main section and each engaged with a packer, and links secured to the lifters and slidably coupled to the collar of the main section connecting the lifters and the main section, the links related to the several packers being of different lengths; whereby the packers engaged by the lifters are successively picked up to move with the main section when the sections are moved relative to each other so the collars move apart.

9. A well packer including, a central body having an elongate vertically disposed main section with a collar fixed thereon, an annular clamp section shiftable longitudinally of the main section below the collar thereof and having a collar thereon, the sections being coupled for limited movement relative to each other longitudinally of the main section, a plurality of separable annular packers in a vertical series on the main section and between the collars, annular members on the main section movable lengthwise thereof and each engaged beneath a packer, and a link connected to each of said members and extending upwardly therefrom through the packers above

75

such members and to the collar of the main section, the several links being of different lengths and connected to the collar of the main section for limited movement relative thereto, whereby the packers engaged by said members are successively picked up and moved with the main section upon the main section being elevated relative to the clamp section.

10. A well packer including, an elongate body having a vertically disposed elongate main section with a collar fixed thereon, an annular clamp section shiftable longitudinally on the main section below the collar thereof and having a collar thereon, the sections being coupled for limited movement relative to each other longitudinally of the main section, a plurality of separable annular packers in a vertical series on the main section and between the collars, annular members on the main section movable lengthwise thereof and each engaged beneath a packer, and links of different lengths connected to said members and extending upwardly therefrom to the collar of the main section and slackly linked thereto whereby the packers engaged by said members are successively picked up and moved with the main section upon the main section being elevated relative to the clamp section, the lowermost packer of the series being below the collar of the clamp section to be picked up thereby when the clamp section moves up with the main section.

11. A well packer including, a central body having an elongate vertically disposed main section with a collar fixed thereon, an annular clamp section surrounding and shiftable longitudinally of the main section and having a collar thereon below the collar of the main section, the sections being coupled for limited movement relative to each other longitudinally of the body, a plurality of separable annular packers in a vertical series on the main section and between the collars, each packer including a vertically apertured annular body of deformable material annular members on the main section movable lengthwise thereof and each engaged beneath a packer, and links of different lengths connected to said members and extending upwardly therefrom to the collar of the main section and each adapted to have limited movement relative thereto, whereby the packers engaged by said members are successively picked up and moved with the main section upon the main section being elevated relative to the clamp section, the links of each member being slidably engaged through the aperture of the bodies of the packers located above that member.

12. A well packer including, a vertical elongate body having a main section with a collar thereon, a clamp section shiftable longitudinally of the main section and having a collar thereon, the sections being coupled for limited movement relative to each other longitudinally of the body, a plurality of separable annular packers in a vertical series on the main section and between the collars, the collar of the clamp element being adapted to approach that of the main section whereby the packers are compressed between the collars, annular members on the main section movable lengthwise thereof and each engaged beneath a packer, and links connected to said members and extending upwardly therefrom to the collar of the main section whereby the packers engaged by said members are successively picked up and moved with the main section upon the

main section being elevated relative to the clamp section, the links being slidably engaged through the collar of the main section and having heads thereon spaced different distances above the collar of the main section when the packers are compressed whereby the links are lifted one after another as the main section is elevated.

13. A well packer including, a vertical elongate body having a main section with a collar thereon, a clamp section shiftable longitudinally of the main section and having a collar thereon, the sections being coupled for limited movement relative to each other longitudinally of the body, a plurality of separable annular packers in a vertical series on the main section and between the collars, annular members on the main section movable lengthwise thereof and each engaged beneath a packer, and links of different lengths connected to said members and extending upwardly therefrom to the collar of the main section whereby the packers engaged by said members are successively picked up and moved with the main section upon the main section being elevated relative to the clamp section, the links of each member being slidably engaged through each packer located above that member and the links being slidably engaged through the collar of the main section and having heads on their upper ends by which the links are lifted successively as the main section is elevated.

14. A well packer including, a vertical elongate body having a main section with a collar thereon, an annular clamp section surrounding and shiftable longitudinally of the main section and having a collar thereon, the sections being coupled for limited movement relative to each other longitudinally of the body, anchoring means carried by the clamp section, a plurality of separable annular packers in a vertical series on the main section and between the collars and adapted to be compressed thereby, annular members on the main section movable lengthwise thereof and each engaged beneath a packer, and links of different lengths connected to said members and extending upwardly therefrom to the collar of the main section and slidably coupled thereto, the links having heads on their upper ends whereby the packers engaged by said members are successively picked up and moved with the main section upon the main section being elevated relative to the clamp section.

15. A well packer including, a vertical elongate tubular body having a main section with a collar thereon, a clamp section shiftable longitudinally of the main section and having a collar thereon, the sections being coupled for limited movement relative to each other longitudinally of the body, means adapted to control flow through the body including valve parts cooperatively engaged when the body sections are in a predetermined position relative to each other, one of the valve parts being carried by the main section of the body, a plurality of separable annular packers in a vertical series on the main section and between the collars, annular members on the main section movable lengthwise thereof and each engaged beneath a packer, and links of different lengths connected to said members and extending upwardly therefrom to the collar of the main section whereby the packers engaged by said members are successively picked

up and moved with the main section upon the main section being elevated relative to the clamp section.

16. A well packer including, a vertical elongate tubular body having a main section with a collar thereon, a clamp section shiftable longitudinally of the main section and having a collar thereon, the sections being coupled for limited movement relative to each other longitudinally of the body, means controlling flow through the body including valve parts cooperatively engaged when the body sections are in a predetermined position relative to each other, anchoring means carried by the clamp section, one of the valve parts being on the main section and the other being cooperatively related to the anchoring means, a plurality of separable annular packers in a vertical series on the main section and between the collars, annular members on the main section movable lengthwise thereof and each engaged beneath a packer, and links of different lengths connected to said members and extending upwardly therefrom to the collar of the main section whereby the packers engaged by said members are successively picked up and moved with the main section upon the main section being elevated relative to the clamp section.

17. A well packer including, a vertical elongate tubular body having a main section with a collar thereon, a clamp section shiftable longitudinally of the main section and having a collar thereon, the sections being coupled for limited movement relative to each other longitudinally of the body, a core extending into the body and related thereto for limited movement relative thereto, means controlling flow through the body including valve parts cooperatively engaged when the body sections are in a predetermined position relative to each other, one of the valve parts being on the main section and the other on the core, a plurality of separable annular packers in a vertical series on the main section and between the collars, annular members on the main section movable lengthwise thereof and each engaged beneath a packer, and links of different lengths connected to said members and extending upwardly therefrom to the collar of the main section whereby the packers engaged by said members are successively picked up and moved with the main section upon the main section being elevated relative to the clamp section.

JESSE GANNON.
